APPARATUS FOR MOLDING SLIDERS FOR
SLIDE FASTENERSJohn Bolten, Jr., Andover, Mass., assignor to The
Bolta Company, Lawrence, Mass., a corpora-
tion of Massachusetts

Application July 14, 1945, Serial No. 605,044

4 Claims. (Cl. 18—42)

1

This invention relates to improvements in moulds for manufacturing sliders for sliding snap fasteners in which tapes having complementary interlocking members pass through spaced openings or mouths in the slider into a relatively narrow passage where they are automatically interlocked as the slider is moved in a direction to cause the interlocking elements to enter the slider and upon reverse movement of the slider to permit separation of the tapes and the interlocking members thereon. Usual moulds for making sliders of this character comprise a stationary and a relatively movable mould section having complementary cavities for the side walls of the slider which are parallel to the contacting surfaces of the mould, and in order to form the passages through the slider it is necessary that the cores, which form the inside of the slider, shall be movable so that the finished product can be removed from the mould. Such cores are usually slid back and forth by mechanical means and there is no possibility of anchoring the free ends of the respective cores in an opposite half of the mould. Such cores are commonly known as "floating cores." In die casting or injection moulding the "floating core" is an undesirable construction and is very likely to lead to breakage or displacement of the end of the core as the cores are not firmly anchored when the molten material is injected or cast into the mould. This is especially important in injection moulding where injection and clamping pressures are from 20,000 pounds per square inch, or more.

One of the principal objects of the present invention is to provide a moulding construction in which complementary cores for the passages through the slider are so interengaged as to avoid the floating condition and insure accuracy and longevity of use.

A further object of the invention is to provide a construction in which the respective cores may be detachably secured in the mould sections and readily replaced if necessary if the core becomes broken, chipped, or otherwise injured.

A further object of the invention is to anchor such replaceable cores so securely in the respective mould halves that for all practical purposes they become a part of the mould and all possibility of play eliminated.

A further object of the invention is to provide a mould construction having a sliding core for forming the pull slot of the usual bridge with means for actuating the core upon relative movement of the mould members to insert the core

2

across the cavity of the mould to form the bridge when the mould members are moved to closed position and to withdraw the slider when the mould members are separated and thereupon to detach the slider from the mould members.

These and other objects and features of the invention will more fully appear from the following description and the accompanying drawings and will be particularly pointed out in the 10 claims.

A preferred embodiment of the invention is illustrated in the accompanying drawings, in which:

Fig. 1 is a side elevation of a conventional 15 type of slider;

Fig. 2 is a vertical sectional view on line 2—2 Fig. 1;

Fig. 3 is an enlarged vertical sectional view of the complementary mould halves in closed position with the cavities of the respective mould halves, which conform to the body of the slide, having their greatest areas registering at the contacting surfaces of the mould and extending inwardly therefrom into the respective mould sections;

Fig. 4 is a vertical sectional view on line 4—4 Fig. 3;

Fig. 5 is a detail view, partially broken away, showing the mould halves in closed position with the core for forming the pull slot of the slide crossing the bridge channel of the mould; and,

Fig. 6 is a view similar to Fig. 5 illustrating the mould members in separated position and the slider withdrawn.

35 A conventional form of slider which is illustrated in Figs. 1 and 2 comprises a slider body having parallel front and rear side members 1 and 2 which are connected together by a central web 3 to provide entrances 4 and 5 for the respective stringers and the complementary series of interlocking members thereon. The entrances 4 and 5 lead to a common guideway 6 having suitably spaced edge walls 7 and 8 to permit the passage of the stringer therethrough. A

40 bridge 9, which is integrally secured at its ends to the side wall 8, provides a pull slot 10 in which the usual puller 11 is slidably mounted. The greatest crosswise area of the slider is at the upper end 12 of the edges 7 and 8 of the slider.

45 As before stated in the usual manufacture of sliders of this type the cavities for the sides 1 and 2 in the respective mould members extend in substantial parallelism with the contacting surfaces of the mould sections and require the use of floating cores as heretofore described. In

50

the present construction the greatest areas of the mould cavities, which correspond to the section 12 of the slider above described, register at the contacting surfaces of the mould members and extend therefrom into the respective moulds in axial alinement. Ordinarily, but not necessarily, the contacting surfaces of the mould sections are in horizontal position and the core sections, which consequently extend perpendicularly to such contacting surfaces, are in vertical position, as illustrated herein. In the construction thus described the upper mould section 13 is in fixed position and the lower mould section 14 is movable downwardly relatively thereto.

As illustrated in Figs. 3 and 4 the lower mould cavity 15 is of downwardly tapering rectangular cross section and is provided with a lateral channel 16 for the bridge. The cavity of the upper mould member which registered with the cavity of the lower mould member is provided with a lateral channel 17 which registers with the channel 16 in the lower mould section and completes the mould for the bridge. The converging passages for the entrance of the stringers which communicate with the common guideway for the interlocking members on the stringers are formed by complementary interengaging core members which preferably are so constructed that the core member in the lower mould section telescopes into the complementary member in the upper mould section. As illustrated herein the core for the lower mould section has a base portion 18 which is fixedly and preferably detachably secured in a complementary socket in the lower mould member and an upwardly extending core 19 which is provided at its upper end with a downwardly curved recess 20, the portion 19 of the core member being of approximately uniform cross sectional area throughout its length.

The upper end of the core member 21 similarly fits in a socket in the upper mould member in axial alinement with the lower core and is provided with downwardly converging side portions 22 and 23 which telescopically engage the upwardly extending core member 19 of the lower mould section. The outer walls of the portions 22 and 23 are so spaced from the wall of the cavity 15 as to provide converging edge walls having inwardly extending flanges 24 and 25, the edges of which are suitably spaced apart to permit the stringer having interlocking members thereon to be guided through the slider. The upper core member is provided with a recess to form a cavity communicating with the cavities for the side walls for forming the web member 3 which connects the side walls of the slider as illustrated in Fig. 2.

Any suitable means may be provided for detachably locking the cores in the respective mould sections. As illustrated herein channels 26 having parallel walls extend transversely into and through the respective mould sections and slightly tapering wedges 27, which are driven into the channels, firmly but detachably anchor the respective core members in place. Obviously any other sort of means may be employed for detachably securing the cores in the respective mould members.

In order to form the bridge 9 a sliding core 28 is mounted in suitable complementary ways 29 and 30 in the upper and lower mould members and crosses the channels 16 and 17 in said members, as shown in Figs. 1, 5, and 6. The sliding core 28 is provided with an inclined slot 31 which extends at a suitable angle to the

longitudinal axis of the core 28. A bar 32, which slidably fits within the slot 31, is provided with an end portion 33 which extends through a boss 34 integral with or welded to the side of the upper mould member. The upper end of the offset extension 33 of the bar 32 is of cylindrical form and is provided with a threaded upper end which is engaged by a nut 35 adapted to clamp the member 32 fixedly in position.

When the mould members are moved to closed position, as illustrated in Fig. 5, the core 28 is forced inwardly across the channel 16-17, as illustrated in Fig. 3. When the lower or movable mould member is separated from the fixed mould member the core 28 is withdrawn as illustrated in Fig. 6.

Suitable means are provided for charging the cavity of the mould. As illustrated herein the upper member of the mould is provided with a sprue 36 which communicates with a gate 37 which in turn preferably communicates with the channel 16-17 of the bridge. When therefore molten material, such as a thermoplastic or die-casting material, is forced under high pressure into the mould it flows through the sprue, the gate and channel 16-17 into the cavities of the mould completely filling them in such manner as to form the side walls with their flanges and the connection between the side walls. When the mould is thus filled and cooled sufficiently to congeal the molten material the lower mould member is separated from the upper, thereby withdrawing the core which forms the pull slot and as the mould members separate the complete slider is withdrawn by the sliding core 28 from the mould sections from which it can be readily removed.

It will be understood that the particular embodiment of the invention shown and specifically described herein is of an illustrative character and is not restrictive of the meaning and scope of the following claims.

Having thus described the invention, what is claimed as new, and desired to be secured by Letters Patent, is:

1. Apparatus for moulding sliders for separable fasteners, of the type having side walls integrally united at one end by an inwardly converging web with the edges of said side walls diverging from said end to a maximum width approximately midway of the length of the slider to provide converging entrance channels for the toothed stringers of said fastener and having converging flanged edges extending from said maximum width merging into parallel flanged edges providing a single relatively narrow channel to cause interlocking of the teeth of said stringers, and a bridge member, integral at its ends with and spaced therefrom from one of said side walls and extending longitudinally thereof, said moulding apparatus comprising a single stationary mould section and a single relatively movable mould section having complementary flat contacting surfaces with complementary cavities having walls conforming to the side members of said slider extending therefrom into the respective mould sections with their greatest cross sectional area registering at said contacting surfaces and complementary axially alined telescopically engaging core members within the respective cavities each extending into the cavity of the other conforming to the converging channels and to the single channels communicating therewith, said core members having cooperating cavities 75 uniting the cavities of said side members to pro-

duce the web uniting them, and longitudinally extending registering channels in the wall of one of said side member cavities providing a cavity for producing the bridge of the slider a sprue hole in the upper mould section and a gate leading therefrom to said bridge cavity, registering ways in the contacting faces of said mould sections extending transversely of said bridge cavity, and a metal core slidably mounted in said ways extending across the bridge cavity for forming the longitudinal pull slot therein.

2. Apparatus for moulding sliders for separable fasteners as defined in claim 1, in which the complementary telescopically arranged core members in the cavities of said mold section are of frangible material and means for detachably securing them in said cavities for removal and for replacement when damaged.

3. Apparatus for moulding sliders for separable fasteners as defined in claim 1, in which the core for producing the slot in the bridge member is slidably mounted in communicating ways in the respective mould sections and means operable by initial separation of the mold members to withdraw the slot-producing core from the bridge cavity and thereby to permit removal of the slider from the mold.

4. Moulding apparatus for the slider of slide fasteners having a bridge extending lengthwise of and spaced from one side of the slider and integrally connected at its ends thereto to form a pull slot comprising a single stationary mould section and a single relatively movable mould section having contacting surfaces, the mould sections having complementary cavities conforming to the side walls of the slider, said mould cavities having their greatest crosswise area registering at said contacting surfaces and extending therefrom into the respective mould sections

and a longitudinal channel for the bridge, complementary telescopically interengaging cores within the respective cavities conforming to the contour of the guideways through the slider having complementary recesses communicating with said cavities to form the web of the slider, means detachably securing the cores to the respective mould sections in axial alinement, a sliding core mounted in complementary guideways in said mould sections adapted to pass transversely through the bridge channel, means for introducing moulding material into the bridge channel to fill the cavities of the mould from both ends, an arm mounted on the stationary mould section and extending downwardly and outwardly therefrom slidably fitting a complementary similarly inclined recess in the end portion of the sliding core operable upon closing of the mould to insert said sliding core through said channel and upon opening of the mould to withdraw said sliding core from the channel and remove the slider from the stationary mould section.
